UNITED STATES PATENT OFFICE.

ANDREW J. MAINE, OF APPLETON, WISCONSIN.

CAR-MOVER.

SPECIFICATION forming part of Letters Patent No. 683,654, dated October 1, 1901.

Application filed July 1, 1901. Serial No. 66,673. (No model.)

To all whom it may concern:

Be it known that I, ANDREW J. MAINE, a citizen of the United States, residing at Appleton, in the county of Outagamie and State of Wisconsin, have invented certain new and useful Improvements in Car-Movers; and I do hereby declare the following to be a full, clear, and exact description of the invention, such as will enable others skilled in the art to which it appertains to make and use the same.

This invention relates to car-movers; and it consists in the novel construction and combination of the parts hereinafter fully described and claimed.

15 In the drawings, Figure 1 is a plan view of the car-mover. Fig. 2 is a sectional side view of the car-mover, showing the parts in a position to be operated. Fig. 3 is a sectional side view showing the car-mover after being 20 operated.

A is a portion of a car-wheel, and B is the rail it runs on.

C is the main lever of the car-mover.

D is the pinch-bar, provided with a pointed 25 end d for going between the periphery of the wheel and the rail. The pinch-bar is provided with a longitudinal slot e, and f is the fulcrum, which extends crosswise of the pinch-bar at the lower part of the slot and which 30 bears on the top of the rail. The other end of the pinch-bar is pivoted to the main lever by a pin d'.

E is a lever pivoted to the pinch-bar by a pin g, which is arranged between the pointed 35 end and the fulcrum f. The lever E works in the slot e and is pivotally connected with the main lever C by a link H. The lever E is provided with a longitudinal slot e', and I is a pushing-lever which is pivoted in the slot e' 40 on a pin i. The pushing-lever I is provided with a slot i' in its rear portion, and j is a pin carried by the pinch-bar D and sliding in the slot i'. The lever E is cranked or bent, so that it does not catch the pin j.

When the main operating-lever C is de- 45 pressed from the position shown in Fig. 1 to the position shown in Fig. 2, the pinch-bar turns on its fulcrum and the front end portion of the pushing-lever is pressed against the car-wheel at a point above the point of 50 the pinch-bar. The connection and proportions of the lever mechanism are such that the front end of the pushing-lever is moved upward against the periphery of the car-wheel with increased speed, and thereby enables the 55 car to be moved with very little force.

What I claim is—

1. In a car-mover, the combination, with a pinch-bar provided with a fulcrum, a main operating-lever pivoted to the pinch-bar, and 60 a lever having its end portions pivotally connected with the said pinch-bar and main operating-lever respectively; of a pushing-lever pivoted to the said lever, and a projection on the said pinch-bar for bearing against the 65 rear part of the said pushing-lever, substantially as set forth.

2. In a car-mover, the combination, with a pinch-bar provided with a fulcrum, a main operating-lever pivoted to the pinch-bar, and 70 a lever provided with a longitudinal slot and having its end portions pivotally connected with the said pinch-bar and main operating-lever respectively; of a pushing-lever pivoted in the said slot of the said lever and provided with a slot in its rear part, and a pin 75 secured to the said pinch-bar and working in the said slot of the pushing-lever, substantially as set forth.

In testimony whereof I affix my signature 80 in presence of two witnesses.

ANDREW J. MAINE.
